& Belknap Attorneys

UNITED STATES PATENT OFFICE.

WILLIAM M. BRECK, OF CLEVELAND, OHIO.

SAFETY-RAZOR-BLADE STROPPER.

Application filed April 24, 1922. Serial No. 556,238.

To all whom it may concern:

Be it known that I, WILLIAM M. BRECK, a citizen of the United States of America, residing at Cleveland, in the county of Cuyahoga and State of Ohio, have invented certain new and useful Improvements in Safety-Razor-Blade Stroppers, of which the following is a specification, reference being had therein to the accompanying drawings.

10 This invention relates to razor stropping devices and more particularly to devices for stropping safety razors.

One of the objects of the invention is to adapt the stropping device for a safety razor 15 blade to be mounted fast upon the razor which is adapted to receive said blade, the handle of the razor thus serving as a handle to the stropping device in use of the latter.

The invention further consists in a novel 20 mechanism for rocking a pivotal blade holder, so as to alternately present the opposed cutting edges thereof to a razor or the like according as the stropping device is alternated in its direction of movement, relative to the strop.

In the drawings:

Figure 1 is a perspective view of the improved stropping device;

Figure 2 is a similar view of the same 30 mounted for use upon a safety razor;

Figure 3 is a sectional view of the device secured to a razor;

Figure 4 is a cross section on lines 4-4 of Figure 3;

35 Figure 5 is a perspective view of the main member of the blade holder;

Figure 6 is a perspective view of an end portion of a complementary element of said holder;

40 Figure 7 is a perspective view of a blade engaging in said holder.

In these views the reference character A designates a frame comprising a pair of end plates A' and a pair of bars B rigidly connecting said plates and preferably integral therewith. C and D are a pair of plates forming the holder for a razor blade, such as is shown at E, said blade being clamped between said plates. The plate D has end 45 members F and G respectively provided with aligned trunnions H, journaled in the plates A'. Said plate D is furthermore formed with a pair of bosses I adapted to snugly engage the openings J formed in the razor 50 blade E and said bosses may project some-

what beyond the blade E to engage in apertures K in the plate C. The latter is held in proper proximity to the companion plate D by the engagement of lugs L formed upon the ends of the plate C with slots M in the 60 members F and G. A leaf spring N secured to the under face of the plate C is adapted to stress said plate to prevent its accidental shifting. O is a supporting element for the frame A and comprises a sheet metal plate 65 slightly curved in cross section and having up-turned ends O' terminally formed with lugs O², which are oppositely bent to engage in slots O³, two of which are formed in each end plate A'. The length of the slots O³ 70 sufficiently exceeds that of the lugs O² to provide for a limited relative reciprocation of the supporting member O and frame A. Each of the end pieces F and G of the blade holder is formed with a circular tongue P, 75 said tongues fitting into correspondingly shaped sockets respectively formed in the ends O' of the supporting plate O. Thus it is evident that relative reciprocation of the plate O and frame A will effect rocking of 80 the blade holder.

R is the handle of a well known type of safety razor, said handle being rigidly secured to a clamping plate S, a companion clamping plate S' carrying a threaded stem 85 T, which is adapted to project into the handle R and is engageable by a tubular stem U, having a head V terminally seating upon the handle R. Thus rotation of the head V will draw the stem T into the stem 90 U and draw the plate S' into clamping relation with the plate S. Said plates, which are slightly arcuate in cross section, are normally adapted to clamp a razor blade, the plate S' carrying a pair of pins W, which 95 may be engaged with apertures J of the clamped blade and which project to also engage suitable openings X formed in the plate S.

The invention adapts the described razor 100 to be employed as a mounting for the described stropping device by giving the plate O a curvature to that of the razor plates S and S' and by forming said plate O with three slots Y extending from one side of said 105 plate to the center portion thereof. Said slots, as is clearly shown in Figure 3, are adapted to accommodate the pins W and stem T, thus adapting the plates S and S' to engage in a clamping relation above and 110

below the member O. When such relation is established, the head is turned to draw said clamping plates into firm engagement with the member O and the stropping device 5 is then ready for use.

In the use of said device the operator manipulates the same by means of the handle R and the manipulation consists in shifting the device back and forth along a strop, such 10 as is indicated in dash lines in Figure 4 at Z. Owing to the frictional pressure of the bars B against the strop there occurs a slight relative reciprocation of the frame A and supporting member O, upon each change of direction 15 in the movement of the device along the strop. The effect of this reciprocation, due to the engagement of the tongue P in the end sockets of the member O is to rock the blade holder at each end of the stroke of the 20 device, so that the advance edge of the razor blade is always slightly raised from the strop while the rear edge of the blade bears against the strop to be sharpened by contact therewith. 25

By utilizing the safety razor from which a blade has been removed as a mounting for the device in which said blade is to be sharpened, the cost of the device is considerably reduced; as compared to devices requiring 30 special handles. Furthermore the described use of a relatively reciprocatory frame and supporting member for the device, the latter being engaged with a blade holder pivoted upon said frame, very positively effects the necessary rocking of the blade holder at each 35 limit of the stropping stroke, so that the danger of cutting the strop is minimized.

What I claim as my invention is:—

1. The combination with a razor blade 40 holder, comprising a handle and clamping means for a blade carried by said handle, of

a stropping device for said blade detachably engageable by said clamping means.

2. The combination with a razor blade holder, comprising a handle and a pair of 45 blade clamping plates transversely mounted terminally upon said handle, of a stropping device having a portion adapted to fit between said plates.

3. A stropping device having a supporting portion engageable between the blade clamping plates of a safety razor.

4. A stropping device having a supporting portion slotted to adapt it for engagement between the blade clamping plates of 55 a razor.

5. The combination with a razor blade holder, comprising a handle and a pair of 60 clamping plates carried by said handle, one of said plates having blade positioning pins projecting toward the other, of a stropping device having a supporting plate slotted to accommodate said pins and to permit said supporting portion to be clamped between 65 said blade engaging plates of a razor.

6. In a stropping device, the combination with a supporting member, of a blade holder including a plate having substantially parallel end portions pivoted on said supporting member, said end portions having recesses 70 therein, and a cooperating clamping plate having relatively short lugs engageable with the recesses in one of said end portions and having relatively long lugs engageable with the recesses in the other end portion of said 75 plate, the last-mentioned lugs being of sufficient length to maintain engagement with their respective recesses while the other lugs are inserted or removed from their respective recesses.

In testimony whereof I affix my signature.
WILLIAM M. BRECK.
